ACOUSTIC DEVICE

Harold C. Pye, Oak Park, Ill., assignor to Associated Electric Laboratories, Inc., Chicago, Ill., a corporation of Delaware

Application July 18, 1932, Serial No. 623,130

4 Claims. (Cl. 179—180)

This invention relates in general to an acoustic device, and the principal object of the invention is to provide an acoustic device utilizing a section of tubing of paper, metal, or other suitable material having a high degree of flexibility, in an economical manner. A flexible tube made in accordance with the invention is adapted for a wide variety of usages, a particular utility being in connection with sound transmitting apparatus. 10 It is, therefore, an object of the invention to provide a damping device for damping the vibrations of sound transmitting apparatus which device has a high degree of efficiency and dependability and which may be easily manufactured and assembled in the sound apparatus.

A further object of the invention is to design a flexible support for diaphragms such as are used in acoustic apparatus so that they may vibrate over their whole surfaces, thereby considerably reducing or eliminating the tendency of the diaphragms to vibrate at their natural period or frequency, which may disturb and distort the sound waves when this frequency falls within the range of the voice frequencies.

25 A particular feature of the invention resides in the design of a flexible member arranged to provide suitable damping means for the diaphragm of sound transmitting apparatus, which at the same time serves as the microphone cell of the apparatus.

The invention is not limited to the production of flexible tubing for use only in sound transmitting apparatus, but is concerned with a flexible tube and the method of making the same for any other purposes to which a tubing of this construction may be put. The tubing may be constructed of metal and thereby be used for the elbows or joints in small pipe line systems; it may be used to form the walls or chambers of an air or hydraulic valve which is adapted to be expanded and compressed; or for any other mechanical purpose where a closed chamber which is expandable and contractible is necessary. The invention, however, is illustrated in connection 45 with only one of the numerous uses for the flexible tube, the other uses being readily perceived without further consideration.

The invention is described and illustrated in accordance with the accompanying drawing which 50 shows a number of different methods of constructing the flexible tube and also an application of the device.

In the drawing, Fig. 1 illustrates the first step in the method of manufacturing a section of flexible tubing; Fig. 2 shows the second step in

which the material has been formed into a hollow tube; Fig. 3 depicts the apparatus in cross-section with the tube inside of the forming apparatus ready to be compressed; Fig. 4 shows the tube in the act of being compressed by the mechanism; while Fig. 5 illustrates a side view of the completed flexible tube. Fig. 6 illustrates a modification of the method of making the tube; Fig. 7 illustrates a further modification of the method of manufacturing the tube; while Fig. 8 illustrates a step in this same method. Figs. 9 and 10 show side and end views of a section of flexible metal tubing construction in accordance with the method of Figs. 7 and 8; Fig. 11 discloses a side cross-sectional elevation of a sound transmitting apparatus, such as a telephone transmitter unit.

In constructing the flexible metal tube in accordance with the preferred method of the invention, a sheet of relatively thin material 5 which is preferably paper, but which may also be thin metal, fibre, or other suitable material, depending on its use, is cut to the desired length and width. The piece of material 5 is then wound around the mandrel 6, preferably so that the ends overlap to a considerable extent. A suitable amount of adhesive may then be applied to the right and left-hand ends of the sheet after it is wrapped upon the mandrel. It is not desirable to apply the adhesive along the overlapping edges of the material as this would have a tendency to stiffening 30 the tube after it is formed. In certain instances the adhesive may be dispensed with as will be apparent hereinafter. After the adhesive has dried upon the mandrel 6, the piece of material is removed from it, and it assumes the smooth form 35 shown in Fig. 2. If seamless tubing is used, the above two steps of course are not necessary.

The next step is to pass the formed tube 5 over the guide rod 7, which, it will be seen, is slightly smaller in diameter than the tube 5. The guide rod 7, together with the tube 5, is then placed inside the hollow cylinder 8. The opening of the cylinder 8 is of such a size that the tube 5 occupies a space approximately midway between the inside surface of the hollow cylinder 8 and the outside surface of the guide rod 7. A pair of hollow cylindrical plungers 9 and 10 are then inserted in each side of the hollow cylinder 8 and over the guide rod 7. These plungers 9 and 10 are shaped to form a very close fit between their surfaces and that of the guide rod 7 and the cylinder 8, with which they are in slideable contact. A suitable amount of pressure is then applied to the plungers 9 and 10 in a direction towards each other as indicated by the arrows so that the tube 5 is al- 50 55

most completely compressed or crumpled together as shown clearly in Fig. 4. The pressure upon the plungers 9 and 10 is then removed and the guide rod 7, together with the compressed tubing 5, is removed from the hollow cylinder 8. The formed tube 5 is then slid off the guide rod 7 and it expands slightly and assumes the shape indicated in Fig. 5.

It will be appreciated that formation of the tube 5 may be done either by hand with the apparatus or may be done automatically by suitable machinery. It will likewise be appreciated that the length of the flexible tube 5 as completed is dependent upon the length of the material supplied in Fig. 1, as well as the amount of pressure applied by the plungers 9 and 10 to the tubing 5. With a wide piece of material and considerable pressure of the plungers, a section of tubing may be produced which is of the same length as a section of tubing which is made of a narrow piece of material upon which very light pressure is applied. The two resultant flexible tubes being of the same length, however, are of different degrees of resiliency, the article—according to the latter method—having very few folds or pleats while the former consists of numerous folds.

The finished section of flexible tube illustrated in Fig. 5 is in the form of a crumpled tube with the folds arranged indiscriminately and at random around the article, and, because of these numerous folds, both large and small interspersed around the circumference, considerable resiliency is imparted to the material of which the flexible tube is constructed. It, therefore, can be easily and readily expanded or contracted without great force or pressure, and, being very light in weight it may be adapted for a considerable number of usages, some of which have been pointed out and some of which will hereinafter be illustrated.

Fig. 6 illustrates a modification of the method of manufacturing a flexible tube from that shown in Figs. 3 and 4 whereby fewer forming parts are necessary. The tube 5 which may be made in the form shown in Figs. 1 and 2 is slid over the end 45 of the plunger 17, and this, together with the tube, is then inserted in the opening in the die 15. A shoulder 16 is formed on the die 15 and a similar shoulder 18 is formed on the plunger 17. As seen in cross-section, the tubing 5 occupies the space 50 midway between the outside surface of the plunger 17 and the inside surface of the die 15. Pressure is then applied upon the plunger 17 either manually or by machine means, and the tube 5 is thereby crumpled together between the 55 shoulders 16 and 18 into the bellows shape, as shown in Fig. 5, with the corrugations or pleats formed at random throughout the circumference of the tube. When the pressure is removed by the plunger 17 being withdrawn, it causes the tube 60 to expand slightly to its proper length due to its resilient nature.

In the above two methods of constructing the flexible tube, it will be appreciated that the length of the tubing is restricted within practical limits. 65 Tubes of this length, however, find a ready use particularly in connection with sound transmitting apparatus, as will hereinafter be pointed out.

A further method of which a flexible tube may be made is shown in Figs. 7 and 8. The tube 5 is made up in a manner similar to that shown in Figs. 1 and 2 and a pair of guide rods 20 and 21 are inserted from each end a sufficient distance into the tube so as to leave a small space indicated as 22. A pair of circular spring clips 23

and 24 are inserted over the outside ends of the tube 5 in order to hold it tight and steady on the guide rods 20 and 21. A slight upward movement is then given to the guide rod 20 and spring clip 23. This results in a kink or crinkled portion 25 being formed in the tube 5. Guide rod 20, together with the spring clip 23, is then pulled out to the right a slight distance from the tube 5. Another kink or twist 26 is then imparted to the tube 5, but in a position, however, at this time 10 approximately 120° from its initial position, thereby forming a different kink on the tube 5. The tube is again moved a slight amount off of the guide rod 20 and spring clip 23, whereupon a further kink or twist 27 is formed which is also 15 approximately 120° turned from the second twist. As seen in Figs. 9 and 10, this successively kinking of the tube 5 at points 120° apart results in a flexible tube as shown, in which the successive kinks are indicated at 25, 26, and 27. A flexible 20 tube of any desired length within practical limits may be constructed with this method.

Referring now more particularly to Fig. 11, this discloses a type of sound transmitting apparatus in which a flexible tube constructed according to the invention may be used. As an example, a transmitter unit has been illustrated. It comprises an ordinary type of solid back transmitter having a casing 30 for supporting the various parts and a floating diaphragm 31 preferably constructed of carbon. In order to minimize the response of the diaphragm 31 more readily to its own natural period of vibration or frequency and thereby distort the speech waves, the diaphragm is of the floating type, that is, it is arranged to vibrate over its whole surface simultaneously and is not supported rigidly around its periphery as is common practice. A flexible paper tube 32 of relatively large diameter is inserted between the turned over edge of the casing 30 and the periphery of the diaphragm 31. If desired, it may be attached to each of these surfaces by means of suitable adhesive. A similar flexible tube 33 is inserted on the opposite side of the diaphragm 31 and also glued to the casing 30. The diaphragm 31 is, therefore, free to vibrate over its complete surface in a lateral direction, and the flexible tubes 32 and 33 resiliently support it without interfering with its freedom of vibration. The tubes also tend to slightly damp the vibrations of the diaphragm 31 when it is actuated so as to further assist in damping out undesirable vibrations within the speech frequency range.

The numerous closely packed folds in the flexible tubes function to damp the diaphragm vibrations by expelling and drawing in the air between the folds when the flexible tube is being compressed and expanded. The effect is to cushion the diaphragm on a successive series of air pockets 60 instead of depending entirely upon the resiliency of each of the folds to produce this result.

The microphone cell of the transmitter comprises a fixed electrode 37 suitably supported and insulated in the rear of the casing 30. The front electrode or moving electrode is formed integral with the diaphragm 31 and consists of a section of the rear side of the same. A flexible tube 35, constructed in accordance with the methods outlined in the invention, forms the enclosure for the microphone cell. A suitable amount of granulated carbon material 36 is supported in the cell by the flexible tube 35. One end of the tube is suitably adhered to the rear side of the diaphragm 31 while the opposite end is attached to the sur- 75

face or face to the fixed electrode 37. Current carrying wires are attached to fixed electrode 37 and the carbon diaphragm 31 in any desired manner. In the operation of the transmitter, speech waves impinge upon the front side of the diaphragm 31, and it vibrates over the whole surface in unison with the speech waves because it is resiliently supported between the flexible tubes 33 and 32. The flexible tube 35 is thereby alternately expanded and contracted in order to agitate the carbon granules 36 and vary the current flow extending over the circuit path including the diaphragm 31 and fixed electrode 37, thereby translating the speech waves into electrical waves. The tube 35 also imparts a slight damping effect upon the diaphragm 31 when it is actuated, thereby minimizing the vibration of the diaphragm 31 so that it does not tend to vibrate at its normal frequency and distort the speech waves. This damping effect is produced by the air cushions between the numerous folds of the tube.

From the foregoing construction of the microphone cell, it will be appreciated that the flexible tube 35 combines a number of functions which have heretofore been performed by separate parts. It forms a complete enclosure for the microphone cell which at the same time is completely insulated by it; it forms a container for the carbon granules 36 to prevent them from being spilt out; and it also exerts a slight damping effect upon the diaphragm 31. The transmitter illustrated can be made extremely cheap and economical; and, because it consists of relatively few parts which are light in weight, it is a very efficient operating transmitting unit.

It will be appreciated that flexible tubes illustrated in connection with the sound transmitter of Fig. 11 are equally applicable to form supports for the diaphragms of receivers, dynamic speak-

ers, phonograph units, and any other place where a flexible support having very little inertia, but which has a slight damping effect, may be utilized.

What is claimed is:

1. In a sound transmitter, a microphone cell containing carbon granules, a front and back electrode in the cell, a flexible tube enclosing the carbon granules and extending between the electrodes, said tube comprising a sheet of paper rolled into a cylinder and compressed to form accordion pleats throughout its length before assembly and acting to retain the carbon in the cell. 10

2. In an acoustic device, a microphone cell, a front and rear electrode therefor, a cylinder extending between the electrodes, said cylinder preformed before assembly in the transmitter from a sheet of flexible material rolled into a cylinder which is compressed to form accordion pleats at 20 random throughout its length, said cylinder holding the granular carbon in the cell. 15

3. In an electrical translating device, a microphone cell comprising a rear electrode and a diaphragm, a series of damping devices for the diaphragm each comprising a tube of flexible material preformed, before assembly into the transmitter, from a sheet of material rolled into a cylinder compressed to form plaited walls, one of 25 said tubes retaining carbon granules in the cell. 30

4. In an electrical translating device, a diaphragm, a damping element for supporting and damping the diaphragm, said element preformed before assembly into the device, from a sheet of flexible material rolled into a tube and compressed 35 to form bellows-like plaitings throughout its length, said plaitings normally tending to elongate the cylinder and thereby damping the diaphragm. 35
